(57) **CLAIM**

The ornamental design for a double-winged radiator for central processing unit, as shown and described.

DESCRIPTION

FIG. 1 is a front elevational view of a double-winged radiator for central processing unit showing our design, a view from the rear being a mirror image;

FIG. 2 is a left side elevational view thereof, a view from the right being a mirror image;

FIG. 3 is a top plan view thereof;

FIG. 4 is a bottom plan view thereof; and,

FIG. 5 is a perspective view thereof.
